J. B. GARDINER AND EDWARD H. HYDE, OF SPRINGFIELD, MASSACHUSETTS.

Letters Patent No. 72,383, dated December 17, 1867.

IMPROVEMENT IN STEAM-PUMPS.

The Schedule referred to in these Letters Patent and making part of the same.

TO ALL WHOM IT MAY CONCERN:

Be it known that we, J. B. GARDINER and E. H. HYDE, both of Springfield, Hampden county, Commonwealth of Massachusetts, have invented certain new and useful Improvements in Steam-Pumps, of which the following is a full and exact description, reference being had to the accompanying drawings, and to letters of reference marked thereon.

This invention consists in the arrangement of a slide-valve, operated by two steam-pistons attached together, and moved by steam let on at either end, by means of a secondary valve, operated directly from a steam-piston, A. To this steam-piston may be attached the plunger of a single-acting or the piston of a double-acting pump.

In the drawings accompanying this specification is shown a diagram of the construction of our improved pump. These improvements we will now more fully describe.

The pump-cylinder C is formed like that of a common plunger-pump, having check-valves attached at a a' , as ordinarily arranged. On the plunger B is cast the piston A, a stuffing-box, b, being interposed between the water-cylinder C and the steam-cylinder D. Fastened to the piston A is the valve-rod c, which at its upper end enters the interior of the small valve E, and moves the same, when the piston works up and down, by the head d striking upon each end of this valve. Ports e e' are arranged in this valve E in such a manner as to communicate with ports f f' , communicating with the two ends of the main valve-chest O, and operating the main slide-valve H by means of the pistons G G' , fitted in the chest at each end, and attached to the slide-valve in such a manner, that although it is perfectly free to press down upon and form a steam-tight joint between the valve and its seat, it is also moved by the movement of the two pistons G G' , which are attached together by the part in which the upper part of the valve H fits.

The operation of this invention is as follows: Steam is let on at P, and passes into the valve-chest O upon the top of the slide-valve H, and also passes from the valve-chest O, through the port r , into the secondary valve-chest R, passing upon and around the valve E. We will then suppose the parts are in the position shown in the diagram. Steam passes in the direction of the arrows upon the valves H and E, and through the port z upon the top of the piston A, forcing it and the plunger B down, and forcing out water at the lower end, through the force-check valve attached to the openings a . When the piston arrives near the lower end of the cylinder, the rod-valve c, moving with it, carries the valve E, so far down in its chest that the port e is brought into communication with the port f , and steam entering through this port f , acts against the piston G' , to drive the slide-valve H so far towards the opposite end of the chest O as to open the small exhaust-port z of the main valve-chest and let out the steam that drives the piston. This motion of the piston G' moves the slide-valve H, and brings the port z into communication with the steam-chest, and the port z' into communication with the exhaust, thus reversing the movement of the piston, and causing it to move upward, drawing up water through the suction-valve attached to the openings a . A similar but opposite movement of the parts, when the piston arrives at the top of the cylinder, reverses the movement of the piston at the end, and thus a continual reciprocating movement of the piston is obtained.

We do not wish to confine ourselves to the exact arrangement herein described, as we may use the engine as a high or low-pressure, single or double-acting, in case a high-pressure single-acting is used, a small amount of steam being always below the piston, and forming a spring to raise it, and in case a low-pressure engine is used, the steam being raised by condensation of the steam on the top of the piston, the water for condensation being taken from the pump in the manner shown in our caveat filed August 28, 1867.

Now, having described our invention, what we claim as new, and desire to secure by Letters Patent, is—

1. The arrangement of the valves E and H, pistons G G' , ports f and e , e' and f' , y and z , y' and z' , substantially as herein set forth.
2. The arrangement, in connection with the said valve-gear, of the valve-rod c, steam-piston A, plunger B, and reservoir C, substantially as set forth.

J. B. GARDINER,
EDWARD H. HYDE.
